WELL CASING FLOATING AND CEMENTING APPARATUS

Thomas M. Ragan, Downey, Calif., assignor to
Baker Oil Tools, Inc., Vernon, Calif., a corpora-
tion of California

Application January 25, 1947, Serial No. 724,447

2 Claims. (Cl. 166—1)

1

The present invention relates to apparatus particularly useful in the floating and cementing of casings, liners and similar conduits in well bores.

A casing string (or liner string) may include an upper float collar and a lower ported shoe or collar having an initially open axial passage. One function of the float collar is to float the casing string to its final position in a well bore, whereupon a tripping or bridging device can be pumped, or otherwise lowered, through the casing, by-passing the valve device of the float collar, and closing the lower axial passage, in order to direct the discharge of cement slurry pumped down the casing laterally outward through the ports of the lower shoe or collar. Following such discharge, the float collar prevents return flow of the slurry into the casing.

An object of the present invention is to provide an improved well casing or liner apparatus of the general character above indicated.

Another object of the invention is to provide a float valve and bridging or tripping apparatus for use in a well casing, or other conduit string, in which a float valve arrangement is employed which can have a larger longitudinal passage than heretofore employed, thus enabling a larger trip or bridge device to be lowered through the passage and by-passed around the valve for the purpose of closing another passage in the casing string below the float valve.

A further object of the invention is to provide a well casing floating and back pressure apparatus embodying a flapper, poppet or similar valve constrained to move in a predetermined path, and a trip or bridge device adapted to open and by-pass around the valve.

One form which the invention may assume is exemplified in the following description and illustrated by way of example in the accompanying drawings in which:

Fig. 1 is a longitudinal section through a string of well casing embodying the present invention.

Fig. 2 is a longitudinal section through the float collar with a tripping or bridging ball in its passage.

Fig. 3 is a view similar to Fig. 2, showing the ball by-passing the valve of the collar.

Fig. 4 is a section taken along the line 4—4 in Fig. 2.

As disclosed in the drawings, a float collar A is interposed in a string of casing B having a shoe or collar C at its lower end provided with a central passage D and lateral ports E above the passage. The collar A consists of an outer steel member or shell 10 connected to adjacent casing sections.

An inner valve body 11 is suitably secured, as by means of intervening concrete 12 or similar material, to the member 10, being provided with an upper tapered guiding surface 13 diverging in

an upward direction and an intermediate cylindrical passage 14 merging into a lower downwardly diverging valve seating surface 15 of generally spherical shape. A rubber or similar seal ring 16 may be inserted in the lower portion of the body to effect a seal with a flapper valve 17 having an outer spherical surface 18 companion to the valve seating surface 15.

The flapper valve 17 has a central arm 19 pivoted on a hinge pin 20 carried by a pair of spaced ears 21 depending from the valve body 11 to one side of its axis. This pin 20 is held in assembled position by a cotter pin 22 at each end engageable with an adjacent ear 21. A spring 23 urges the flapper valve 17 toward closed position by swinging it on its hinge or pivot pin 20 toward engagement with the seal ring 16 and spherical body surface 15. As disclosed in the drawings, this spring 23 may be disposed around the hinge pin 20 on both sides of the valve arm 19, the ends 24 of the spring bearing against the steel tubular member 10 of the collar, and the central portion 25 of the spring extending inwardly to engage the main portion of the flapper valve 17 itself and urge it toward closed position against the co-operable seat 15, 16.

In the arrangement disclosed by way of example in the drawings, it is desired to close the axial passage D through the lower shoe or collar C, in order to direct the fluid pumped down through the casing string outwardly through the shoe or collar ports E. To accomplish this purpose, a suitable trip or bridging member 26, such as a ball, is lowered through the casing string and is pumped through the collar body 11, displacing the flapper valve 17, to one side and continuing on downwardly below the flapper valve into engagement with the seat 27 at the upper end of the shoe axial passage D, preventing fluid from passing downwardly through this passage and directing all of the fluid outwardly through the side ports E.

For the purpose of displacing the flapper valve 17 sufficiently to one side against the action of the spring, the tripping member 26 has a diameter substantially equal to the inside diameter of the cylindrical body passage 14 in order to have a slidable sealing fit therewith. As a result, this tripping member, upon entering the cylindrical passage 14, functions as a piston, the fluid under pressure behind the piston tripping member 26, forcing it downwardly through the cylindrical passage and causing it to engage the flapper valve 17 and displace it to one side until the ball 26 passes out of the body 11 and along and around the flapper valve 17, whereupon it can drop downwardly through the casing string toward the shoe C. As a matter of fact, the passage of the ball through the cylindrical body portion 14, upon application of pump pressure to the fluid thereabove

and around the valve member 17 is extremely rapid, the ball in effect being shot out of the passage 14, rapidly forcing the flapper valve member to one side to an open position in which the ball 26 rides off the free end of the member 17.

In the use of the apparatus, the casing string may be floated through the fluid in the well bore until the casing string has been lowered to its desired position. During such downward running action, the flapper valve 17 remains closed against the seal ring 16 and also against the spherical seat 15. A good leak-proof seal is provided since the flapper valve is mounted freely on the hinge pin 20 and can move laterally to a slight extent in order that the spherical seating surfaces 15, 18 may engage properly. Such lateral movement is permitted without losing sealing contact with the seal ring 16 since the latter projects inwardly from the body to a substantial extent and will deform laterally. After the casing has been run into the well, the trip or bridging ball 26 is lowered down through the casing string, being pumped through the cylindrical passage 14, by-passing around the flapper valve 17 (Fig. 3) and coming to rest on the seat 27 at the upper end of the lower shoe or collar passage D, thereby preventing further downward flow of fluid through this passage and confining all fluid flow laterally outward through the side ports E.

Cement slurry may now be pumped down, through the casing string and past the valve 17 for outward passage through the side ports E and for deposition behind the string of casing. Following the placing of the required quantity of slurry in the annulus around the casing string, the pumps may be stopped and the flapper valve 17 will engage its seat 15, 16 to prevent return flow of slurry through the ports E into the casing string.

The use of a device like the flapper valve 17, which may be displaced to one side of the collar A, enables a larger trip or bridging ball 26 to be employed in closing the central passage D through the lower shoe or collar and also enables this passage to have a relatively large diameter. It will be evident that the thickness of the flapper valve is much less than the diameter across the flapper valve itself, and that it can be swung open to a greater extent before contacting the tubular member 10 than ball valve and similar devices heretofore used can be displaced laterally from the central collar passage. Accordingly, a larger central passage can be used and a larger ball or other trip device 26 may be pumped, piston-like, through the passage 14 and past the flapper valve 17. This is particularly true of the small sizes of float collars, in which it is still desired to employ a comparatively large trip or bridge device 26, despite the fact that the extent of downward swinging movement of the float valve member 17 is limited by its engagement with the wall of the tubular member 10.

As a matter of fact, it is to be noted that it is unnecessary for the flapper valve to be displaced completely to one side of the central passage 14 through the valve body 11 since the ball 26 can pass between the valve 17 and seat 15, 16, while the former occupies an inclined position almost fully within the path of fluid flow through the 70 central valve body passage (see Fig. 3).

It is important to note that the trip or bridging member 26 makes a sliding sealing fit with the cylindrical passage 14 to cause it to swing the flapper valve 17 in a downward direction sufficiently to allow the member 26 to by-pass the valve 17. Any substantial leakage past the ball while it is contained within the cylindrical body passage 14 would merely allow the fluid to flow around the ball and open the flapper valve to a slight extent, then flowing down through the casing below the collar. Under these circumstances, the flapper valve itself would not open sufficiently to permit by-passing of the ball 26. The functioning of the trip device 26 as a piston, however, through making a snug sliding fit with the cylindrical body passage 14, causes it to be acted upon by the fluid and forced directly against the valve member 17, opening the latter until it is displaced around the member 17 to a position of freedom for continuing its downward travel toward the seat 27 at the upper end of the axial passage D through the lower shoe or collar C.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. Apparatus of the character described, including a tubular member adapted to form part of a well casing string, a body secured to said member and having a cylindrical passage therethrough and a valve seat at the lower end of said passage, a valve member pivotally mounted on said body, spring means engaging said valve member to swing said valve member upwardly into engagement with said seat, and a ball movable downwardly through said cylindrical passage and past said valve member, said ball having a diameter substantially equal to the inside diameter of said cylindrical passage.

2. Apparatus of the character described, including a tubular member adapted to form part of a well casing string, a body secured to said member and having a cylindrical passage therethrough and a valve seat at the lower end of said passage, a valve member pivotally mounted on said body for upward swinging into engagement with said seat, and a member moveable downwardly through said cylindrical passage and completely past said valve member, said downwardly moveable member having a diameter substantially equal to the inside diameter of said cylindrical passage.
